ADOLF SCHOLZ, OF NEW YORK, N. Y.

FEED-WATER REGULATOR.

1,372,199.

Specification of Letters Patent. Patented Mar. 22, 1921.

Application filed November 5, 1919. Serial No. 335,798.

To all whom it may concern:

Be it known that I, ADOLF SCHOLZ, a citizen of the United States, and resident of the city of New York, in the county of New York and State of New York, have invented a certain new and useful Feed-Water Regulator, of which the following is a specification.

This invention relates to automatic feed-water regulators, and particularly to the type utilized in connection with low pressure boilers.

The principal object of my invention is to provide a simple, inexpensive, conveniently 15 and economically manufacturable, efficiently operating, and improved feed-water regulator, which may be installed conveniently and economically, and when in operation will not get out of order.

Another object of my invention is to provide a feed-water regulator, of the stated type, which while having increased efficiency over regulators used heretofore and greater responsiveness than that possessed by such 25 regulators to changing water-level conditions in the boiler, will in addition thereto be compact, of reduced weight and volume, and possessed of increased strength, durability and general reliability.

Other objects and advantages will herein-after appear.

The accompanying drawing shows a general sectional elevation of the automatic feed-water regulator.

The tank 1 of the regulator comprises an uprightly disposed cylinder 2 having a head 3 secured to its upper end and a head 4 secured to the lower end thereof. A pipe 5 secured to the central portion of the lower 30 head 4 passes therethrough and leads therefrom to the lower part of the water in the boiler, not shown, and thereby connects the lower part of the chamber in the tank 1 with the water in the boiler. And a pipe 6 secured to the upper head 3 passes therethrough and leads therefrom to the upper or steam portion of the boiler. Water from the boiler therefore enters the tank 1 and reaches therein a level similar to that in the 45 boiler, and the tank is so located relatively to the level of the boiler that when the water in the boiler is at the proper required level the water-level in the tank 1 reaches at about midway between its heads 3, 4. Within 50 the tank 1 is located a spherical shell 7, which is movable upwardly and downwardly

therein and is guided in said movement by means of a stem 8 that extends into the pipe 5 and is secured to a flange 9 which is in turn secured to said shell. One or more perforated disks 10 are mounted upon the stem 8 with their peripheries fitting against the wall of the pipe 5, whereby the stem and the shell 7 joined thereto are guided to slide vertically in their movements, the axes of 65 the stem, shell, and the cylinder 2 being in alinement.

Above the upper head 3 is located a valve 11 that comprises a casing 12 having a hub 13, that threads through the central portion 70 of the head and is by this means secured thereto, and a fitting 14 that threads into the upper end 15 of the casing. The fitting 14 is provided with a passageway or inlet 16, and a feed-water pipe 17 is connected to the 75 upper end of the fitting, whereby the feed-water coming from the pipe 17 passes through the inlet 16 and enters the chamber 18 in the casing 12, wherefrom it passes out through an outlet 19 that forms part of said 80 casing. Said outlet is joined to a pipe 20 which is in turn connected with the lower part of the water portion of the boiler. A stem 21 is slidably mounted in an opening 22 formed in the lower part of casing 12 and 85 hub 13, from which opening the upper part of said stem extends into the casing-chamber 18, and its lower part projects into the interior of tank 2, the axes of the stem 21 and the inlet 16 being both in alinement with the 90 axes of the tank, shell 7, and stem 8. The upper extremity of stem 21 is formed in the configuration of a flange 23, upon the top of which is secured a rubber, soft lead, or other flexible washer 24, and a spring 25 is 95 coiled around the stem 21 between its flange 23 and the bottom of chamber 18, whereby said spring normally presses the stem upwardly and tends to cause the flange 23 with the washer 24 to bear against the seat 100 26, formed by the lowermost extremity of the fitting 14, and to close the passage-way 16. A lever 27 having a plate 28 formed at the extremity thereof which is located near the right-hand side of the tank-wall 2, as viewed 105 in the drawing, is fulcrumed at 29 to a hanger 30 depending from the underside of the upper head 3 at some distance to the left of the projecting stem 21. Swinging of the lever 27 upwardly about its fulcrum 110 causes a cam-portion 31 thereof to bear against a cupped depression 32 formed in

the extremity of stem 21 and to thereby apply pressure of the flange 23 against the seat 26 in addition to the pressure supplied by the spring 25, while releasing of said lever 5 removes its pressure from the stem 21 and permits the lever to drop to the position shown, whereupon it can fall no farther due to its extremity 32 abutting against a detent 33 formed upon the hanger 30.

10 The spring 25 is possessed of a pressure which is, to a certain predetermined extent, lower than that of the water-mains or the incoming feed-water. And therefore as the water in the lower pressure boiler drops 15 from its required level, due to evaporation or other losses, the feed-water coming in through the pipe 17 and down the passage-way 16 thrusts the stem 21 downwardly, and passing by the flange 23 enters the boiler for 20 its replenishment, through the outlet 19 and the feed-pipe 20. As the water level in the boiler thus becomes restored the water level in the tank 1 rises similarly and elevates the hollow buoyant shell 7 accordingly, and in 25 doing so the shell bears against the plate 28, swings the lever 27 upwardly against the stem 21, and in this manner compels the latter to exert pressure against the seat 26 in addition to that supplied by the spring 30 25, whereby the inlet 26 becomes effectively sealed and the water theretofore fed to the boiler is completely shut off. Should the water-level in the boiler now again drop to any extent, the shell 7 would sink accordingly and consequently release the lever 27, 35 which would drop downwardly to the same extent and releasing its pressure against the stem 21 would thereby permit the feed-water to thrust the stem 21 downwardly 40 contrary to the pressure of its spring 25, and to pass by its flange 23 and into the boiler for its replenishment. When the shell 7 maintains its pressure against the plate 28 of lever 27 to shut off the feed-water, 45 a plate 34, forming part of a hanger 35 secured to the head 3, rests against the opposite or left hand side of the shell to compensate for the pressure which it exerts against the plate 28 and to thereby equalize 50 the lateral pressure against the shell, which would otherwise tend to produce an undue bending stress in the stem 8 or undue contact of the shell with the left hand wall of the tank 1.

55 As the pressure of modern water-systems or city mains is far higher than the internal pressure of low-pressure boilers, it has been found necessary heretofore to make the shells or floats, ordinarily utilized 60 in connection with feed-water regulators, of considerable size to overcome the high pressure of the feed-water for proper operation of the valves of such apparatuses, and, as a further consequence, the tank and the

rest of the regulator parts had to be made 65 proportionally larger. But in this regulator the spring 25 serves the purpose of overcoming such excessive pressure of the feed-water and the shell 7 is only required to carry or overcome the surplus pressure, or that 70 pressure which is the difference between the spring and feed-water pressures, and therefore the shell 7 being required to carry a comparatively small load for operation of 75 the valve it can be made of minimum diameter, with the tank and other parts similarly reduced in size, which results in a more compact and cheaper apparatus and in various other obvious advantages. It will be evident that the requirement of shell 7 to 80 overcome only surplus pressures results in greater regulative responsiveness of the apparatus to varying water-lever changes in the boiler, since buoyant bodies are naturally more responsive to exerting pressure to 85 overcome lesser loads than they are to overcoming greater loads. The coöperation of lever 27 with the shell 7 further amplifies the pressure against the stem 21, and hence is further conducive toward attaining effective pressure for shutting off the feed-water, with a shell of minimum diameter and maximum of compactness of the apparatus. It will be also evident that the freedom had by the shell 7 in sinking away 90 from the lever 27, and by the lever in turn dropping away from the stem 21, due to disconnection of these parts, upon loss or diminution of required water-level in the 95 boiler, is conducive toward a maximum of 100 regulative responsiveness of the apparatus, since there are no joints connecting these parts, which joints might tend to stick and thereby become derogatory to the immediate action required of these parts to respond 105 to even the slightest water-level changes in the boiler. It will be noted that the regulator can be very readily assembled, by merely placing the shell 7 in the tank 1 with its 110 stem 8 in the pipe 5, securing the head 3 to said tank, threading the valve 11 upon the head, and making the usual water and steampipe connections. The arrangement by which the axes of stem 21 and the inlet 16 are both in alinement with the axis of 115 the tank, results in the simplest, most direct, and efficient operation of the working parts of the regulator, and in the simplest, most economical, and convenient assemblage of the regulator. A drip valve 36 120 is preferably provided to discharge water from the tank for cleaning purposes and also when trying out the regulator. When the shell 7 drops to the bottom of the tank when the water is withdrawn from the 125 boiler for repair purposes, the flange 9 protects the wall of the shell against injurious contact with the bottom of the tank.

Variations may be resorted to within the scope of the invention, and portions of the improvements may be used without others.

Having thus described my invention, I
5 claim:—

- inlet adapted to move toward and away therefrom, a spring having a pressure lower than that of the incoming feed water pressing said stem toward said inlet, a lever 5 adapted to swing toward and away from said stem, said body striking said lever when moving upwardly and releasing the lever when sinking, and means to guide said body laterally upon its striking said lever.
10. 7. A feed-water regulator having the combination with a tank, and a vertically movable buoyant body therein, of a member having a feed-water inlet, a valve for closing said inlet adapted to move toward and 15 away therefrom, a spring having a pressure lower than that of the incoming feed-water pressing said valve toward said inlet, a lever adapted to swing toward and away from said valve, said body striking said lever 20 when moving upwardly and releasing the lever when sinking, and means to limit the swinging of said lever when released by said body.
8. A feed-water regulator having the combination with a vertically movable buoyant body, of a valve having an inlet for feed-water, means for closing said inlet, resilient means bearing against said closing means with a pressure lower than that of the 25 incoming feed-water, a lever adapted to swing toward and away from said closing means, said body adapted to move toward and away from said lever, and said body when rising operating said lever to therewith exert pressure against said closing means in addition to the pressure exerted by said resilient means.
9. A feed-water regulator having the combination with a vertically movable buoyant 30 body, of a valve having an inlet for feed-water, means for closing said inlet, resilient means bearing against said closing means with a pressure lower than the incoming feed-water, an intermediate element movable 35
- toward and away from said closing means, 45 said body adapted to move toward and away from said element, and said body when rising operating said element to therewith exert pressure against said closing means in addition to the pressure exerted by said resilient means.
10. A feed-water regulator having the combination with a vertically movable buoyant body, of a valve having an inlet for feed-water, means for closing said inlet, resilient means bearing against said closing means with a pressure lower than that of the incoming feed-water, said body being disconnected from said closing means and 50 adapted to move toward and away from said closing means, and said body when rising causing exertion of pressure against said closing means in addition to the pressure exerted by said resilient means.
11. A feed-water regulator having the combination with a vertically movable buoyant body, of a valve having an inlet for feed-water, means for closing said inlet, a lever adapted to swing toward and away from said closing means, said body adapted to 55 move toward and away from said lever, and said body when rising operating said lever to therewith exert pressure against said closing means.
12. A feed-water regulator having the combination with a vertically movable buoyant body, of a valve having an inlet for feed-water, means for closing said inlet, an intermediate element movable toward and away from said closing means, said body adapted to move toward and away from 60 said element, and said body when rising operating said element to therewith exert pressure against said closing means.
- Signed at the city of New York, in the county of New York, and State of New York, this 3rd day of November, A. D. 1919.
